UNITED STATES PATENT OFFICE.

ALBERT ULLMAN, OF CLEVELAND, OHIO, ASSIGNOR TO SCOTT-ULLMAN COMPANY, OF CLEVELAND, OHIO, A CORPORATION OF OHIO.

DESIGN FOR A RING FOR LIGHTING FIXTURES.

59,992.

Specification for Design.

Patented Dec. 13, 1921.

Application filed April 11, 1921. Serial No. 460,503. Term of patent 3½ years.

To all whom it may concern:

Be it known that I, ALBERT ULLMAN, a citizen of the United States, residing at Cleveland, in the county of Cuyahoga and State of Ohio, have invented a new, original, and ornamental Design for a Ring for Lighting Fixtures, of which the following is a specification, reference being had to the accompanying drawing, forming part hereof, wherein—

Figure 1 is a side elevation and Fig. 2 is a bottom plan view of a ring for lighting fixtures exhibiting my new design.

I claim:—

The ornamental design for a ring for lighting fixtures, as shown.

ALBERT ULLMAN.
